DRAFT APPLIANCE AND THE LIKE

Filed Sept. 27, 1928

UNITED STATES PATENT OFFICE

CHARLES E. CARPENTER, OF CHICAGO, ILLINOIS

DRAFT APPLIANCE AND THE LIKE

Application filed September 27, 1928. Serial No. 308,624.

This invention has to do with certain improvements in draft rigging for railroad cars and the like. The invention has to do with the construction of the draft rigging as a whole; but it has reference particularly to improvement in the means for buffering and taking up the recoil and shock incident thereto.

This invention has reference, amongst other things, to improvements in the friction creating devices whereby the energy of the recoil is dissipated in the form of friction, with consequent generation of heat. This heat is, of course, promptly dissipated into the surrounding parts and the atmosphere.

One object of the invention is to provide a friction device which will be very effective in its function and which will be capable of promptly dissipating a large amount of energy within a relatively small space.

In connection with the foregoing, a further object is to provide an arrangement whereby the friction will be steadily increased as the amount of movement of the coupler increases, thereby producing an increased resistance to further coupler movement. This will also assist in bringing about a rapid dissipation of the energy of the recoil.

A further object of the invention is to provide an arrangement such that a very smooth and effective operation will be insured, thus still further eliminating unnecessary shock and providing a more satisfactory operation.

Another object of the invention is to provide a draft rigging construction of simple form and one which can be manufactured relatively cheaply and at the same time built into a very rugged and substantial form of structure.

A further object of the invention relates to the provision of an improved construction of draft rigging in which substantially all of the operating and friction creating and absorbing devices are located between the frame bars. This will bring the entire structure into a relatively small compass and greatly facilitate application of the same to the standard car construction.

A further object of the invention relates to the provision of an improved construction such that the creation of the friction for ab-

sorbing the energy of the recoil is co-incident with the tendency to restore the draft appliance and coupling member to the central position when the pull or push on the coupler is discontinued.

Other objects and uses of the invention will appear from a detailed description of the same which consists in the features of construction and combinations of parts herein-after described and claimed.

In the drawings:

Figure 1 shows a horizontal plan view of a draft appliance embodying the features of the present invention, the parts standing in their central or neutral position;

Fig. 2 shows a longitudinal section taken substantially on the line 2—2 of Fig. 1 looking in the direction of the arrows;

Fig. 3 shows a cross section on the line 3—3 of Fig. 1 looking in the direction of the arrows;

Fig. 4 shows a cross section on the line 4—4 of Fig. 1 looking in the direction of the arrows;

Fig. 5 shows a perspective view of one of the centering or wedging blocks which are located at the ends of the movable box or housing; and

Fig. 6 shows a perspective view of one of the companion friction blocks.

Referring first to Fig. 1 the central floor sills or frame bars of the car frame are shown at 7 and 8. They are usually spaced a definite distance apart which is a standard distance in most car constructions. I have illustrated top and bottom plates 9 and 10 extending across the sills 7 and 8 and secured to them so as to establish a longitudinally extending housing within which the draft appliances are located.

Within this housing there is located a U shaped bracket member 11 having the top and bottom flanges 12 and 13 joined together at their front ends by the yoke portion 14. Said yoke portion is provided with a pair of lugs 15 and 16 which receive between them the rear end of the stem 17 of the coupler 18. Said coupler is pivotally connected to said lugs by means of the pin 19 so as to allow for the necessary lateral swings of the cou-

pler. A boxing or head 20 is set into the front end of the car frame, having an opening 21 of sufficient size to take care of the lateral movements of the coupler.

- 5 Secured between the upper and lower arms 12 and 13 are the front and rear wedge shaped wedge blocks 22 and 23. One of these is shown in perspective in Fig. 5. It includes a tongue 24 the front end of which is beveled to establish the friction faces 25 and 26, and the rear portion of the block is provided with a cross member 27 which reaches practically the full width of the space between the sills 7 and 8 (with the exception 10 of the thickness of shoes which may be permanently secured to said sills.)

At the rear end of the tongue 24 there are provided the additional tapered or beveled faces 28 and 29.

- 20 The blocks 22 and 23 are preferably of the same construction and size and are interchangeable or reversible. Furthermore these blocks are preferably made of hardened steel or other material capable of withstanding the severe usage which will be imposed upon them in actual service.

The blocks 22 and 23 are preferably secured to the arms 12 and 13 by rivets or other pins 30 (see Figs. 1 and 2). Consequently 30 these blocks travel back and forth with the yoke 11. Located between the flange portions 27 of the blocks 22 and 23 are the friction shoes 31 and 32. These are pressed outwardly by springs 33 located between the 35 corner portions and guided by pins 34. Said pins are either separate from the shoes or are divided so as to allow the shoes to move outwardly under the force of the springs. In the construction illustrated the pins are carried in bushings 35 located in the corners of the shoes.

The shoes 31 and 32 either bear directly against the sills 7 and 8 or against shoes 36 and 37 which are secured to the inner faces 45 of the sills by riveting or otherwise. The arrangement is such that the end flanges 27 of the blocks 22 and 23 travel inside of the shoes 36 and 37, but the shoes 31 and 32 travel with said end blocks. Consequently 50 the back and forth movements of the coupler and of the yoke 11 are communicated to the shoes 31 and 32 and the latter resist such back and forth movement due to the friction of their pressure against the shoes 36 and 37.

- 55 The tongue 24 of each of the blocks 22 and 23 is longitudinally slotted as shown at 38; and a fixed pin 39 reaches through the corresponding slotted opening 38 and the end portions of said pin are secured to the sills 7 60 and 8. As a matter of strength of construction and arrangement the ends of the pins 39 are extended through the sills and are received in the bushing blocks 40 and 41 which are riveted to the outside faces of the 65 sills. Consequently said pins are very rigid-

ly held against back and forth movements and there is provided a very strong construction capable of withstanding severe shocks. There is a pair of friction shoes 42 and 43 corresponding to each of the blocks 22 and 23. The shoes of each pair are centrally perforated as shown at 44 to receive the corresponding pin 39 so that the shoes are held against any longitudinal movement but are allowed to slide back and forth towards and from each other. These shoes are provided with bevel faces 45 and 46 corresponding to the bevel faces of the block 22 or 23 as the case may be, so that as the said blocks are moved back and forth in harmony with the 70 coupler the wedge blocks 42 and 43 are subjected to corresponding and simultaneous forces of separation, or are allowed to move together as the case may be.

The wedge blocks are forced inwardly by 75 heavy springs 47 placed on the pins 39.

The parts are so proportioned that when the coupler stands in the central position illustrated in Fig. 1 the wedge blocks of each pair are forced towards each other a maximum distance and until their faces 48 come finally against the faces of the corresponding tongue 24. Any movement of the coupler in one direction or the other is then attended by a wedging action at the one end or the other of the draft appliance depending on the direction of such movement. For example when the coupler is placed under tension the blocks 22 and 23 will be moved towards the left in Figs. 1 and 2, thereby separating the 100 wedge blocks 42 and 43 at the left hand end and allowing the generation of a simultaneous heavy friction with the wedge blocks at the right hand end. In that connection it will also be noted that the tendency of the 105 beveled faces 25 and 26 is to wedge between the outer ends of the blocks 42 and 43 so as to separate them and thus cause them to pivot about their central portions due to the force of the springs 47. This will in turn wedge the inner ends of said wedge blocks more firmly 110 against the bevel surfaces 28 and 29 to thereby increase the friction at this point.

From the above analysis it is perfectly evident that this arrangement is very efficient for the generation of a maximum amount of friction.

Due to the heavy friction existing between the blocks 42 and 43 and the corresponding blocks 22 or 23, I prefer to make said wedge 120 blocks also of hard steel so as to properly withstand the wear to which they are subjected.

It will also be noted that by so proportioning the parts that both pairs of wedge 125 blocks are fully forced together when the coupler stands in the central position, there is a centering action produced from both directions, tending to restore the coupler to its central position from either direction. In 130

this connection it will be noted that the bevel surfaces 25, 26, 28 and 29, together with the corresponding surfaces of the wedge blocks are at an angle of substantially 45°. Consequently the restoring forces of the spring 47 will result in recentering the draft appliance since this angle is not sufficient to cause the wedge blocks to lock solidly against the blocks 22 and 23.

It will also be noted that the inner ends of the wedge blocks are provided with stop faces or shoes which are adapted to come against companion stop faces 50 on the blocks 22 and 23 so as to completely arrest relative longitudinal movement at the extreme limits desired. Reference to Fig. 1 in particular shows that when the coupler is in the central position these shoes 49 are considerably separated from said stops 50, this amount of separation representing the total amount of coupler movement available in that direction before the parts will jam.

It will be noted that by placing the collars or bushings 40 and 41 against the outside faces of the frame sills I am able to establish an ample clearance for the accommodation of the wedge blocks as well as the springs 47 and at the same time allow for a substantial amount of lateral separating movement of the wedge blocks in service. At the same time this arrangement does not necessitate any serious cutting of the sills since it is only necessary to drill the centers for the accommodation of the pins 39.

While I have herein shown and described only a single embodiment of the features of my present invention still I do not intend to limit myself thereto except as I may do so in the claims.

I claim:

1. The combination with the underframing of a car including the central longitudinally extending parallel frame bars, of a bifurcated yoke movably mounted between said frame bars for backward and forward movement, a coupler pivotally connected to the front end of said yoke, front and rear end blocks rigidly secured within said yoke and separated from each other a distance to establish a box space between them, a pair of side friction plates located in said box space and having outwardly facing friction faces for cooperation with fixed friction faces on the frame bars, springs tending to separate said side friction plates and force them against said fixed friction faces, said end blocks being provided with endwise projecting central wedge lugs having wedge faces on the inner and outer ends of said lugs, there being longitudinally extending slots in the wedge lugs, transverse pins fixedly located with respect to the frame bars and extending through said slots, wedge blocks slidably mounted on said pins, and having wedge faces cooperating with the wedge faces on the wedge lugs, and

springs located between the wedge blocks and the frame bars and serving to force the wedge blocks towards each other, substantially as described.

2. The combination with the underframing of a car including the central longitudinally extending parallel frame bars, of a bifurcated yoke movably mounted between said frame bars for backward and forward movement, a coupler pivotally connected to the front end of said yoke, front and rear end blocks rigidly secured within said yoke, and separated from each other a distance to establish a box space between them, friction devices within said box space and travelling with the yoke, means for frictionally engaging the friction devices with the parallel frame bars aforesaid, said end blocks being provided with endwise projecting central wedge lugs having wedge faces on the inner and outer ends of said lugs, there being longitudinally extending slots in the wedge lugs, transverse pins fixedly located with respect to the frame bars and extending through said slots, wedge blocks slidably mounted on said pins and having wedge faces cooperating with the wedge faces on the wedge lugs, and springs located between the wedge blocks and the frame bars and serving to force the wedge blocks towards each other, substantially as described.

3. The combination with the underframing of a car including the central longitudinally extending parallel frame bars, of a bifurcated yoke movably mounted between said frame bars for back and forth movement, a coupler pivotally connected to the front end of said yoke, front and rear end blocks rigidly secured within said yoke and separated from each other a distance to establish a box space between them, a pair of side friction plates located in said box space and having outwardly facing friction faces for cooperation with fixed friction faces on the frame bars, springs tending to separate said side friction plates and force them against said fixed friction plates, said end blocks being provided with endwise projecting central wedge lugs having wedge faces on said lugs, wedge blocks mounted for movement towards and from said wedge lugs, means for retaining said wedge blocks against movement parallel to said wedge lugs, said wedge blocks having wedge faces cooperating with the wedge faces on the wedge lugs, and springs located between the wedge blocks and the frame bars and serving to force the wedge blocks towards each other, substantially as described.

4. The combination with the underframing of a car including the central longitudinally extending parallel frame bars, of a bifurcated yoke movably mounted between said frame bars for back and forth movement, a coupler pivotally connected to the front end of said

yoke, front and rear end blocks rigidly secured within said yoke and separated from each other a distance to establish a box space between them, friction devices within said box space and travelling with the yoke, means 5 for frictionally engaging the friction devices with the parallel frame bars aforesaid, said end blocks being provided with endwise projecting central wedge lugs, having wedge faces 10 on said lugs, wedge blocks mounted for movement towards and from said wedge lugs, means for retaining said wedge blocks against movement parallel to said wedge lugs, said wedge blocks having wedge faces 15 cooperating with the wedge faces on the wedge lugs, and springs located between the wedge blocks and the frame bars and serving to force the wedge blocks towards each other, substantially as described.

20 5. The combination with the underframing of a car including the central longitudinally extending parallel frame bars, of a member movably mounted between said frame bars for back and forth movement, a coupler pivotally connected to the front end of said member, front and rear wedge blocks rigidly secured to said member, said wedge blocks being provided with endwise projecting central wedge lugs having the wedge surfaces of 25 the two lugs facing away from each other, there being pairs of opposite wedge faces on said lugs, wedge shoes mounted for movement towards and from said lugs, means for retaining said wedge shoes against movement 30 parallel to said lugs, said wedge shoes having wedge faces co-operating with the wedge faces on the wedge lugs, and springs serving to force the wedge shoes towards each other and into engagement with the wedge faces 35 on the lugs, and spring pressed means carried by the movable member cooperating with the frame bars to exert a constant friction therewith during movement of the movable member, substantially as described.

40 6. The combination with the underframing of a car including the central longitudinally extending parallel frame bars, of a member movably mounted between said frame bars for back and forth movement, front and rear 45 end blocks rigidly secured to said member, said end blocks being provided with endwise projecting central wedge lugs, pairs of wedge faces on said lugs, said pairs of wedge faces on the two lugs being convex outwardly, to- 50 wards the opposite ends of the device, wedge shoes mounted for movement towards and from said wedge lugs, means for retaining said wedge shoes against movement parallel to said wedge lugs, said pairs of wedge shoes 55 having wedge faces cooperating with the wedge faces on the wedge lugs, said wedge faces on said pairs of wedge shoes being concave inwardly against the faces of the lugs, and spring means serving to force the pairs 60 of wedge shoes towards each other to thereby 65

establish frictional engagement against the wedge lugs and establish a centering force tending to move the movable member to a central position, and spring pressed means carried by the movable member cooperating 70 with the frame bars to establish a constant friction therewith during movement of the movable member, substantially as described.
